UNITED STATES PATENT OFFICE.

WILLIAM WARREN McCARTER, OF QUITMAN, GEORGIA.

CASTING-MACHINE.

1,072,480.

Specification of Letters Patent. Patented Sept. 9, 1913.

Application filed October 26, 1912. Serial No. 727,989.

To all whom it may concern:

Be it known that I, WILLIAM W. McCARTER, a citizen of the United States, residing at Quitman, in the county of Brooks 5 and State of Georgia, have invented a new and useful Casting Machine; and I do hereby declare the following to be a full, clear, and exact description of the invention, such as will enable others skilled in the art to 10 which it appertains to make and use the same.

This invention relates to a new and useful casting machine adapted for making or casting turpentine dip barrel or similar 15 rims.

As one of the objects of the invention, it is the aim to provide a device of this nature having a stationary mold member with an annular cavity substantially semi-elliptical 20 in cross section, and a movable mold member including a cavity therein shaped correspondingly to the first cavity, in combination with a lever and yoke, for reciprocating the movable mold member within a frame.

The invention comprises further features 25 and combination of parts, as hereinafter set forth, shown in the drawings and claimed.

In the drawings:—Figure 1 is a view in 30 side elevation of the improved casting machine constructed in accordance with the invention. Fig. 2 is a plan view. Fig. 3 is a sectional view on line 3—3 of Fig. 2. Fig. 4 is an end view. Fig. 5 is a view in end elevation, opposite to that shown in Fig. 4. 35 Fig. 6 is a sectional view on line 6—6 of Fig. 1, showing a turpentine dip barrel rim in section, and the movable mold member in elevation.

Referring more particularly to the drawings 40 Fig. 1 designates a frame or stand, which comprises the side guide bars 2, which at one end of the frame terminate in downwardly extending portions 3 connected by a transverse bar or base 4 at their lower 45 ends. The guide bars 2 at their other ends are connected by the transverse bar 5. A mold member 6 which is annular in contour, is provided. Projecting from the outer circumference of the mold member 6, and upon 50 each side thereof is a lug 7. Bolts or screws 8 pass through the lugs 7 and into the guide bars 2, so as to hold the mold member 6 stationary upon the frame or stand, and against the bar 5. The mold member 6 is 55 provided with an annular mold cavity 10,

which is substantially semi-elliptical in cross section, as a preferable contour. Another member 11 is provided having a similar cavity 12. The two mold members are provided with slight recesses adapted to register when the two mold members are brought together, thereby forming a pouring opening, through which the metal, such as lead or other material is poured, so as to reach the cavities in the mold members. 60 The mold member 11 is provided with laterally extending lugs 15 adapted to slide upon the parallel side bars 2 of the frame. 65

Each of the mold members is provided with a central opening 16. Projecting from 70 the wall of the opening of the mold member 11, and extending slightly inwardly are lugs 17, to which the ends 18 of the yoke 19 are held by the cotter pin 20. The yoke 19 is in turn pivoted at 21 by the bolt 22 to the 75 lever 23, which in turn is pivoted in the bracket arms 24, which form a part of the transverse bar 4. The pivot of the lever to the bar 4 is in the form of a bolt 25.

When casting the turpentine dip barrel 80 rims, the mold member 11 is brought in contact with the mold member 6, after which the lead or other material is poured through the opening between the two mold members, so as to reach the cavity, thereby forming 85 the rim. After the material has become thoroughly set, the mold member 11 is reciprocated rearwardly upon the bars 2, by the manipulation of the lever 23. When separating the mold members the free 90 end of the lever 23 is swung backwardly, until its extremity rests upon the surface on which the casting machine rests. When moving the lever 23 to this position the yoke 95 moves the movable mold member backwardly, the lugs 15 sliding upon the guide bars 2. Owing to the fact that the yoke is always pulling downwardly and rearwardly it tends to hold the lugs 15 firmly and 100 squarely in contact with the guide bars, which will hold the movable mold member substantially in a vertical position and substantially against oscillation. After the movable mold member has been moved rearwardly, it still remaining in a vertical position, and it being found that the casting 105 adheres in the cavity of the movable mold member, the yoke 19 may be swung upon its pivot to the lever 23, thereby entirely removing the movable mold member clear 110

2
of the guide bars with its cavity facing upwardly, after which the casting may be lifted from the cavity.

The invention having been set forth, what is claimed as new and useful is:—

In combination, a frame comprising parallel side guide bars, a stationary mold member carried by the forward portions of said side guide bars, a movable mold member having laterally extending lugs adapted to slide upon said side guide bars; said mold members having registering depressions adapted to form a casting cavity with a pouring opening; a lever pivoted to the rear bottom portion of said frame; a yoke pivotally connecting said lever and the movable mold member, whereby the movable mold member may be reciprocated longitudinally upon the guide bars; said yoke, by

virtue of the lever, adapted to pull down- 20
wardly and rearwardly on the movable mold member, thereby holding the laterally ex-
tending lugs firmly and squarely in contact
with the guide bars; said movable mold
member, upon oscillating the lever rear- 25
wardly on its pivot and the yoke in the same
direction, upon its pivot with said lever,
adapted to be removed clear of the guide
bars with its depression facing upwardly,
whereby the casting may be easily lifted in 30
case it adheres.

In testimony whereof I have signed my
name to this specification in the presence of
two subscribing witnesses.

WILLIAM WARREN McCARTER.
